UNITED STATES PATENT OFFICE

160,810

SEWING MACHINE

Karl Scheiwiller, Rosenberg, St. Gallen, Switzerland, assignor to Brutsch & Co., St. Gallen, Switzerland

Application November 1, 1949, Serial No. 5,823
In Switzerland July 15, 1949

Term of patent 14 years

(Cl. D70—2)

To all whom it may concern:

Be it known that I, Karl Scheiwiller, a citizen of the Swiss Confederation and residing at Rosenberg, St. Gallen, Switzerland, have invented a new, original, and ornamental Design for a Sewing Machine, of which the following is a specification, reference being made to the accompanying drawing, forming part thereof.

Fig. 1 is a perspective view of the sewing machine with the swingable support in operative position and showing my new design; Fig. 2 is a view similar to Fig. 1 but seen from the opposite side thereof;

Fig. 3 is a view similar to that of Fig. 1 with one side of the swingable support swung to inoperative position.

I claim:

The ornamental design for a sewing machine, substantially as shown.

KARL SCHEIWILLER.
